UNITED STATES PATENT OFFICE.

HERBERT ALLEN WHEELER, OF ST. LOUIS, MISSOURI.

SMOKELESS FURNACE.

SPECIFICATION forming part of Letters Patent No. 579,910, dated March 30, 1897.

Application filed March 9, 1896. Serial No. 582,512. (No model.)

To all whom it may concern:

Be it known that I, HERBERT ALLEN WHEELER, a citizen of the United States, residing in the city of St. Louis, in the State of Missouri, have invented new and useful Improvements in Smokeless Furnaces, of which the following is a specification.

My invention relates to improvements in the fireboxes or furnaces of boilers, kilns, roasting, calcining, and heating furnaces and other devices where the production of heat without smoke is desired with a maximum economy of fuel, with a uniform maintenance of heat, an avoidance of the waste of fuel that arises in cleaning fires when using grate-bars, and a minimum cost in the erection and maintenance of the furnace; and with these objects in view my invention consists of the novel devices and combinations hereinafter described and specifically claimed.

In the accompanying drawings, on two plates, Figure 1 is a longitudinal section through the fireplace and boiler. Fig. 2 is a front elevation of the fireplace, and Fig. 3 is a plan of the fireplace with the top plate *m* removed to better show the construction.

Similar letters refer to similar parts in all the drawings.

Of the various applications that may be made of this very economical, inexpensive, smokeless furnace I have shown it applied to a steam-boiler *A* for making steam, as this is the field in which there is the greatest demand for a smokeless, inexpensive, durable furnace, especially to overcome the smoke nuisance in large cities, but I do not limit the furnace to this field, as there are many other applications where these features are very valuable and desirable, as in kilns for lime, cement, and claywares, roasting, calcining, and heating furnaces, or for any purpose where the most economical production of heat is desired with the avoidance of smoke and a minimum cost of erection and repair of the furnace.

The design herein described is to overcome the objections to the perishable fire-pots and other ironwork shown in my application for patent for a "Smokeless Economizer Furnace," Serial No. 574,529, filed January 6, 1896, by substituting fire-brick, which will

cost less to erect, be very much more durable in withstanding heat, and will not be subject to the warping and cracking of the exposed ironwork therein shown and described, while 55 it has the same advantages of economy in fuel and smokeless character of the fire of my prior device.

The boiler *A* is hung by lugs *C* on the side walls *B* in the usual manner, while the up- 60 take *E* and stack *F* are of the usual pattern common in boilers.

Instead of usually carrying the fire or grate bars *x*, as in current practice, I prefer when the fuel permits to employ a dead or solid bottom *l*, of fire-brick, that sets on a sand cushion *k*. The fuel is fed through the firing-hole *c* into a fore chamber *w* and spreads out on the solid bottom *l* to the base of the fire-bridge *G* and into the ash-pit archway *e*. The fore chamber *w* is kept filled with fuel to at or about the firing-hole *c*. Air is supplied for carrying on the combustion at the base of the fore chamber *w* through the ash-pit arch *e*, which extends across the fireplace and 70 through the firing-hole *c*. A curtain-wall *b*, that is carried by an arch *g*, of fire-brick or other suitable material, separates the fore chamber *w*, into which the fuel is fed, from the combustion-chamber *a*, which latter is 80 formed by the curtain-wall *b*, the fire-bridge *G*, and the two side walls *B*. The fire-bridge *G* is backed by earth filling *H* in the usual manner, which latter is sloped back to the rear of the boiler, as shown. 85

The fore chamber *w* is formed by the curtain-wall *b*, the front wall of fire-brick *d*, and the corbelled fire-brick walls *h*, that drop back to the special side walls *i* of the fore furnace. By corbeling these side walls *i* the firing-hole 90 *c* is contracted to a size suitable for feeding the fuel and cleaning the walls of clinkers without admitting too much air if it was too large, while they conform in outline to the slope that the fuel takes in falling when fed 95 into the fire-hole *c*.

The front wall *d* has the ash-pit arch *f* at its base for the admission of air, the removal of clinkers, and the cleaning of the fire through the doorway or opening *e*, which is covered by 100 a swinging door *g*, that is hung on hinges *r*, that are suspended from a front plate *n*, of

east-iron or other suitable material, that is held in place by anchor-bolts *s*.

The top of the fore furnace is protected by a metal plate *m*, of cast-iron or other suitable material, that is held in place by the anchor-bolts *t* and which has the firing-hole *c*. The firing-hole *c* is covered by fire-clay tiles *p* or by a hinged door or other suitable device.

The curtain-wall *b* is protected and supported by the front plate *o*, of cast-iron or other suitable material, that is anchored by the anchor-bolts *v*. Special back staves and tie-rods *D'* support the arch *g*, that carries the curtain-wall *b*.

15 The side walls *B* are held together by the back staves and tie-rods *D'* in the usual manner.

The operation of the furnace or fire-box consists in filling the fore chamber *w* with 20 coal or other fuel, after lighting in the usual manner, up to or about the firing-hole *c* and leaving the ash-pit door *q* and the firing door or hole *c* open. The fuel spreads out in a 25 conical pile from the front wall *d* to the fire-bridge *G* and into the ash-pit *e*. The air enters through *e*, as the door *q* is kept open, and in passing through the mass of fuel in the lower portion of the fore chamber *w* creates 30 an intense heat in front of the arch *f*, which so softens the ashes of the fuel into a clinker that it slowly runs as a pasty mass out into the ash-pit *e*, where from time to time it is removed. As the air passes through the 35 thick bed of fuel it first oxidizes the latter into carbonic acid, (CO_2), but this is converted into the imperfectly-burned condition of carbonic oxid (CO) as it passes farther into the incandescent fuel, and loss of fuel would result if it did not meet with an excess of oxygen that enters with the air as a downdraft through the fire-hole *c*, for an excess of air enters through the firing-hole *c* through the 40 upper part of the fore chamber, and as the bed of fuel is thin through which it passes to 45 reach the arch *g* at the base of the curtain-wall only a portion of its oxygen is consumed; but it is raised to a high temperature, so that in entering the combustion-chamber *a* the 50 conditions of time, space, and temperature are favorable for it to perfectly burn the carbonic oxid, hydrocarbons that are distilled from the fresh fuel, and other combustible gases, for the large space, highly-heated surrounding walls of fire-brick, and time allowed 55 for mixing and burning in the combustion-chamber *a* result in a high heat, perfect combustion, and the avoidance of smoke. The lower portion of the fore chamber *w* thus largely performs the function of a gas-producer in making carbonic oxid, while the upper portion, with its restricting-curtain *b*, performs the function of a downdraft reheating-furnace for preheating the air before it enters the combustion-chamber *a*. If the fuel in the 60 upper portion of *w* is kept too deep, it will become more of a gas-producer than a pre-heater, and insufficient air will enter to in-

sure perfect combustion, while if the depth of fuel is kept too thin it will not sufficiently heat the air to insure perfect combustion in *a*. 70

The design of the furnace enables, with moderate experience, the maintenance of the proper depth of fuel in the upper portion of *w* above the arch *g*, according to the size and kind of fuel, to secure perfect combustion. 75

The fuel is added frequently and in small amounts, which prevents the admission of cold air if the fuel-level is kept above the crown of the arch *g*, and this insures uniformity of temperature, which is so desirable for boilers, kilns, and heating-furnaces, as it prolongs the life of the furnace and boiler and adds greatly to the quality of the ware in burning clay goods. 80

The long period required for the fuel to pass 85 from *c* to *e* gives it time to be completely burned, so that only clinkers, slag, and ashes fall out at *e*, which are removed from time to time, and the more frequently they are removed the higher the heat will be, while it 90 avoids the waste of fuel that occurs when cleaning grate-bars of clinkers, when more or less unburned fuel is always hauled out with the clinkers in the usual practice. The fore chamber *w* projects sufficiently in front of 95 the boiler to enable the front wall *d* and curtain-wall *b* to be cleaned of adhering clinkers with a sharp bar through the firing-hole *c*, while the clinkers that adhere to the bottom and sides of the furnace are removed through 100 the ash-pit doorway *e*.

The absence of ironwork that is exposed to a high heat and the simplicity of the construction of the furnace result in a low cost of erection and maintenance. 105

The ash-pit door *q* may be hung on overhead or side hinges or hung on rollers or operated by sliding doors or any other convenient way.

The ash-pit doorway *e* may be made as a 110 simple large arch that spans the entire width of the furnace or it may be subdivided into two or more smaller spans.

The firing-door *c* may be made of one large central opening or it may be subdivided into 115 two or more smaller openings. It may be covered with fire-clay tiles or hinged doors, rolling doors, sliding covers, or by any other convenient way or any other suitable material.

The front wall *d*, curtain-wall *b*, special 120 side walls *i*, corbelled walls *h*, fire-bridge *G*, and bottom *l* may be made of fire-brick, stup, ganister, or any suitable refractory material.

When the fuel is slack, sawdust, or other material that will not admit sufficient air, or where for any reason it is preferable to use grate-bars instead of firing on a dead bottom, then grate-bars *x*, carried on bearing-bars *y*, as shown in Fig. 1, are employed. The high economy in fuel, the perfect combustion, and the avoidance of smoke are still prevented when using grate-bars, but the cost of erection and repairs is greater than when using a solid or dead bottom. 125 130

What I claim as my invention, and desire to secure by Letters Patent, is—

1. A furnace comprising the solid front wall *d*, the ash-pit arch *f* located in the front wall, the solid curtain-wall *b*, the arch *g* located in the curtain-wall, the downdraft firing-hole *c*, and fore chamber *w*, located between the front wall and the curtain-wall, the corbelled walls *h*, the fire-bridge *G*, the combustion-chamber located between the curtain-wall and the fire-bridge, and the fuel-bottom *l* extending beneath the curtain-wall, the firing-hole and the combustion-chamber, substantially as described.
- 15 2. A furnace comprising the solid front wall

d, the ash-pit arch *f*, located in the front wall, the solid curtain-wall *b*, the arch *g* located in the curtain-wall, the downdraft firing-hole *c*, and fore chamber *w* located between the front wall and the curtain-wall, the corbelled walls *h*, the fire-bridge *G*, the combustion-chamber located between the curtain-wall and the fire-bridge, and the fuel-bottom *l* extending beneath the front wall, the curtain-wall, the firing-hole and the combustion-chamber, substantially as described. 20 25
